LOCKING DEVICE FOR INTERFITTING MEMBERS

Howard Spencer Charles, Toronto, Ontario, Canada, assignor of one-half to Henry Charles Morris, Toronto, Ontario, Canada

Application October 18, 1947, Serial No. 780,664

5 Claims. (Cl. 287—119)

1

My invention in its general aspect relates to locking devices for interfitting connections particularly of the type in which telescopic members are secured together.

An object of the invention is to provide a highly efficient and serviceable locking device for telescoped members, and one which is easy to operate and inexpensive to manufacture.

A further object of the invention is to provide a reliable locking device of the character referred to and one which functions to positively lock telescoped members in interfitting connection without any likelihood of their becoming inadvertently detached.

The invention comprehends a locking device in which a pin is transversely fitted in a socket member eccentrically within its bore, and in which a male member is telescoped in the bore, the telescoped end thereof being provided with a locking passage in which said pin is received, said locking passage being disposed at one side of the telescoped end to extend parallel to the axis thereof from a front stop face rearwardly to a thrust face which abuts said pin under pressure supplied by a spring. Said stop face is continued around the telescoped end and at the opposite side there is provided a flat which extends to the end face of the telescoped end to form a guide passage which communicates with said locking passage by means of a circularly extending groove adjacent to said stop face. The structure provides for attachment of the male member by telescoping its end in the bore of the socket member with the guide passage positioned in register with the pin to bring the stop face into abutment with the pin. Then the male member is turned through an angle of 180°. In the turning movement the pin passes through the circular groove and the locking passage receives the pin. The spring then acts to force the male member outwardly until the thrust face engages the pin. The male member is thus locked to the socket in a positive manner and cannot be turned in either direction.

The invention affords a secure locking device which has several uses. For instance, it is admirably suited for fastening the handle to a fishing rod. It is also susceptible of use for making a detachable connection between the head and the shaft of a golf club.

In the embodiment of the invention shown in the accompanying drawing the locking device is applied to a fishing rod.

In the drawing,

Fig. 1 is a fragmentary side view, partly in

50 detail, of an ordinary fishing rod handle and the handle 8, which is designed to be applied thereto, and which includes a locking device 10, having a flat 20, a pin 14, a helical compression spring 11, a stop shoulder 18, a thrust shoulder 19, a locking passage 15, a flat bottom face 16, a stop face 17, a guide passage 21, and a lateral groove 22.

Fig. 2 is a cross section taken on line 2—2 of Fig. 1.

Fig. 3 is a similar view to Fig. 1, but shows how the rod is telescoped in the handle before it is turned to a locked position.

Fig. 4 is a plan view of the telescoping end of the rod.

Fig. 5 is a cross section on line 5—5 of Fig. 4.

Fig. 6 is a side elevation of Fig. 4.

Fig. 7 is an end view of Fig. 6.

The reference numeral 8 denotes an ordinary fishing rod handle having an offset portion 9 forming a seat for a reel. The forward end 10 of the handle constitutes a rod-receiving portion and is in the form of a socket whose bore is indicated at 11. The inner end 12 of a rod 13 is telescoped in said bore to provide an interfitting connection.

In carrying out the present invention the socket portion 10 of the handle is provided with a pin 14 transversely fitted therein to project through the bore 11 eccentrically thereof so as to be disposed at a side thereof. Said pin is located in the vicinity of the outer end of the bore and constitutes a fixed projection. A helical compression spring 11' is seated at the inner end of the bore.

The telescoped end 12 of the rod is cut away at one side to provide a locking passage 15 having a flat bottom face 16 parallel to the axis of the rod. The locking passage is of a depth to loosely receive the pin 14 and it is remote from the inner end face 17. The forward end face 18 of the locking passage constitutes a stop shoulder and the rear end face 19 constitutes a thrust shoulder.

Said stop shoulder 18 is continued around the telescoping end to the opposite side thereof to a flat 20 by means of an adjacent lateral groove 21 which extends circularly and is of an arcuate cross section to accommodate the pin and allow it to pass therethrough when the rod is turned. Said flat 20 is of a depth to receive the pin and it extends from the stop shoulder 18 to the end face 17 in order to form a guide passage.

In the use of the locking device the inner end 12 of the rod 13 is telescoped in the bore 11 of the socket against the tension of the spring 11' and with the flat 20 positioned in register with the pin 14 so that the pin will be received in the guide passage, see Fig. 3. Said inner end 12 is pushed in the bore as far as it will go, i. e., until the stop shoulder 18 abuts the pin, whereupon the

rod is turned by hand through an angle of 180° which brings the locking passage 15 into register with the pin. The groove 21 accommodates the pin to permit the turning movement of the rod. When the telescoping force is relaxed the spring 11 forces the rod in outward direction until the thrust shoulder 19 abuts the pin. In this way the locking device securely attaches the rod to the handle and permits of its being readily detached.

The locking device is reliable and efficient. Moreover it is inexpensive to manufacture and has the advantage that the telescoped members are held against relative angular movement.

While the locking device has been described by way of example as applied to a fishing rod it will be understood that it is susceptible of other uses.

What I claim is:

1. A device of the class described comprising a first member having a bore, a second member having an end telescoped in said bore, a pin carried by said first member transversely projecting into said bore at a side thereof, said telescoped end being cut away at one side to provide a locking passage in which said pin is disposed, said locking passage extending longitudinally of said telescoped end and being formed with a stop shoulder at its forward end and a thrust shoulder at its rearward end, said telescoped end being formed with a flat opposite said locking passage, said flat extending forwardly from the extremity of said telescoped end and terminating in a stop face aligned with said stop shoulder, said flat providing a guide passage for said pin and communicating with said locking passage by means of a forwardly disposed groove receptive to said pin, and means yieldably urging said telescoped end outwardly so that said thrust shoulder is held in engagement with said pin.

2. A device of the class described comprising a first member having a bore, a second member telescoped in said bore thereof and having an inner end face, a projection rigid with said first member and disposed in said bore at a side thereof, said second member being reduced at a side to form a longitudinally extending locking passage in which said projection is disposed, said locking passage being spaced from said end face and forwardly terminating in a stop shoulder and rearwardly terminating in a thrust face, said stop shoulder being continued around said second member to the opposite side thereof by means of an adjacent lateral groove receptive to said projection, said opposite side being reduced to form a flat which extends from said stop shoulder to said end face to form a guide passage receptive to said projection, and a spring on said first member outwardly tensioning said second member so that it will be yieldably held with said thrust face engaged with said projection.

3. A locking joint of the class described, com-

prising a socket element, a cylindrical member for telescoping therein, the socket element having a transverse pin eccentrically extending through its bore at a side thereof, the cylindrical member having a locking passage at one side, a guide passage at the opposite side and a circularly extending groove at the forward end of the passages, the locking passage being spaced from the inner end face of the cylindrical member and being formed with a thrust shoulder for engaging the pin, the guide passage being open at said inner end face to admit the pin so that it can pass to said groove and into said locking passage by a turning movement of the cylindrical member, and a spring lodged in said socket element for urging the cylindrical member outwardly of the socket portion of said socket element to cause said thrust shoulder to engage the pin.

4. A device of the class described, comprising a socket section, a cylindrical section for telescoping therein, the socket section having a transverse pin therein at a side of its bore and having a spring for urging the cylindrical section, the cylindrical section having an inner end face and having a longitudinal flat at one of its sides spaced from said end face and terminating in a forward end face and a rearward end face to form a locking passage receptive to the pin, the forward end face forming a stop shoulder and the rearward end face forming a thrust shoulder, the cylindrical section also having an arcuate groove receptive to the pin, said groove being disposed at the forward end of the locking passage, said cylindrical member also having a longitudinal flat opposite said first mentioned flat and extended from said end face to merge into said groove to provide a guide passage forwardly terminating in a stop shoulder, whereby the cylindrical member can be telescoped in the socket section with the guide passage aligned with the pin and then turned so that the pin will pass through the groove into the locking passage for abutment with the thrust shoulder thereof when the cylindrical member is forwardly urged by the spring, whereby to bring about a locking engagement.

5. A device as set forth in claim 4, in which the spring is seated in the socket section for engaging the inner end face of the cylindrical section.
